Fig. 5

Fig. 6

FIG. 1 is a front elevational view of a pull for drawers, doors or the like showing my new design;

FIG. 2 is a side elevation thereof;

FIG. 3 is a rear elevation thereof;

FIG. 4 is a side elevation thereof oriented 180 degrees from the position shown in FIG. 2;

FIG. 5 is an end elevation taken from the left of FIG. 4;

FIG. 6 is an end elevation taken from the right of FIG. 4.

The diametrically opposed end members of the pull are substantially the same.

I claim:

The ornamental design for a pull for drawers, doors or the like, as shown and described.
